CLAIM

The ornamental Design for a tire, as shown and described.

DESCRIPTION

FIG. 1 is a right side perspective view of a first embodiment of a tire;

FIG. 2 is a left side perspective view thereof;

FIG. 3 is a front elevational view thereof;

FIG. 4 is a right side elevational view thereof;

FIG. 5 is a left side elevational view thereof;

FIG. 6 is an enlarged fragmentary front elevational view thereof;

FIG. 7 is a right side perspective view of a second embodiment of a tire;

FIG. 8 is a left side perspective view of a second embodiment; and,

FIG. 9 is a front elevational view of a second embodiment. In the drawings, the broken lines immediately adjacent to the outer edges of the tire shoulder represent boundaries of the claim, and the broken lines depict environmental subject matter only and form no part of the claimed design.
